W. S. HARRIS

Des. 163,949

BEDSTEAD

Filed Jan. 25, 1950

FIG. 2

FIG. 1

INVENTOR

William S. Harris

UNITED STATES PATENT OFFICE

163,949

BEDSTEAD

William S. Harris, Arlington, Va.

Application January 25, 1950, Serial No. 7,474

Term of patent 3½ years

(Cl. D5—5)

To all whom it may concern:

Be it known that I, William S. Harris, a citizen of the United States, residing at Arlington, Arlington County, Virginia, have invented a new, original, and ornamental Design for a Bedstead, of which the following is a specification, reference being had to the accompanying drawing, forming part thereof.

I claim:

The ornamental design for a bedstead, as shown.

WILLIAM S. HARRIS.
